UNITED STATES PATENT OFFICE.

EDWARD F. WOOD, OF WASHINGTON, DISTRICT OF COLUMBIA, ASSIGNOR TO THE AMERICAN CAR DOOR HANGER COMPANY, COMPOSED OF EDWARD F. WOOD, GEORGE C. HAVENNER, FRANCIS G. BOSWELL, AND ROBERT A. BOSWELL, ALL OF WASHINGTON, DISTRICT OF COLUMBIA.

DOOR-HANGER.

1,183,154.

Specification of Letters Patent. Patented May 16, 1916.

Application filed November 4, 1910. Serial No. 590,736.

To all whom it may concern:

Be it known that EDWARD F. WOOD, a citizen of the United States of America, residing at Washington city, District of Columbia, has invented a new and useful Door-Hanger, of which the following is a specification.

This invention belongs to the class of hangers, being particularly a hanger adapted for freight car doors, which permits the door to be used in the most efficient manner.

By the hereinafter described construction of hanger, the door is enabled, when being closed or opened to freely slide, and which hanger comprises further features and combination of parts, as hereinafter set forth, shown in the drawings and claimed.

In the drawings:—

Figure 1 is a view of a portion of a side of a car disclosing the improved hanger construction as applied, as an illustrative showing of the application of the hanger.

Figure 2 is a sectional view through the upper part of the side of the car, showing the upper rail in plan view, and showing a part of the upper hanger.

Figure 3 is a view in elevation of the hanger, showing the hanger rail in section.

Figure 4 is an enlarged cross sectional view on line 4—4 of Figure 3, showing the hanger rail, and illustrating the hanger connected to an operating crank rod of the door.

Figure 5 is a sectional view of the hanger at one end of the door of the car opposite the end having the crank rod.

Figure 6 is a sectional view on line 6—6 of Figure 5.

Figure 7 is a detail view in perspective of the part 16.

In the figures, in which similar characters of reference designate similar parts, *d* is a door for the car body *c*. It is hung on the hangers *b* and *b'* which run in the track *t*.

The hanger *b* is provided with a stirrup *s* which is composed of the arms 1 emanating from and integral with the cap 2. The depending ends of the arms 1 meet and blend into an enlarged portion 3 of the hanger, there being integral with this portion 3 a depending stud 4 provided with a head 5. This hanger is secured to the door by means of the plate 6 and the cover plate 7 with the aid of suitable bolts 8. The hanger is thus

capable of a swiveling motion in its supports and sustains the weight of the door on the head 5.

The hanger *b'* is substantially the same as *b*, with the exception that instead of the stud 4, it has a larger but much shorter stud 9 which penetrates the eye of the crank rod 10 and is secured therein by a washer 11 and cotter-pin 12.

The caps 2 of the hangers are formed into globular shaped pockets of slightly larger radii than the balls 13. With this method of mounting the balls, their surfaces are at all times tangent to the surfaces of the pockets and they are thus permitted to slip therein and to slide along the track *t*.

The track *t* is composed of two semi-circular rails 14 and 15, sustained by the aid of the J bolts 17, and the screws 18, which pass through the spacing blocks 16 and into the car body. In this manner the rails 14 and 15 are secured in such a position as to provide a cylindrical bearing surface for the balls 13. For a portion of their height, the spacing blocks conform to the cross-sectional outline of the innermost rail 14 and thus offset the tendency of the track to be drawn in towards the car body. A metal cover 19 (of L section), running the entire length of the track, covers the rail flanges and the spacing blocks. This cover is held by the J bolts 17, as they support the track, and provides what is known as a watershed.

The bottom sides of the rails 14 and 15 are separated a short distance to permit the passage of the depending hanger arms 1.

The track *t*, for the greater part of its length, runs parallel to the car body, but, at a point about in the middle of the door opening, it is directed in towards the car, terminating at a point just sufficient to allow the offset hanger *b* to hold the door in flush with the car body.

The spacing blocks for the deflected portion of the track do not curve around the circular portion of the rail 14 but rest only against the flange.

The rod 10 is provided with a collar 20. Four strap bearings 22 cover this rod and are fastened to the door *d* by bolts 23. Suitable plates 24 are interposed between these straps 22 and the door and set behind the rod 10. One of the straps 22 is just above

the collar 20, to support the weight of the door at this end.

The upper end of the rod 10 is bent over and provided with an eye which encompasses the stud 9 of the hanger *b'* where it is secured as before stated, and is capable of turning on said stud. That end of the rod remote from the eye terminates in an offset end 25 which cooperates with the guide 10 track *g*.

The track *g* is composed of an outer guard rail 26 and a backing plate 27. It is mounted on the blocks 28 which are held in position by the bolts 29 and screws 30. 15 The guard rail 26 follows the same outline as the hanger track *t*, being deflected in toward the car body at the end. The backing plate 27 runs the entire length of the track *g* and between the car body and the 20 blocks 28. For a portion of its length it bends over the blocks and, in conjunction with the guard rail 26, provides a guideway for the lower mechanism of the door. At 25 the point where the guide rail begins to deflect, the capping portion of the backing plate gradually diminishes and finally disappears, leaving only the thickness of the plate at the closing end of the door.

The blocks 28 at this end are, therefore, 30 not provided with the portion for supporting the cap.

The object of this backing plate, besides providing a guideway and an operating slot for the crank rod, is to prevent any 35 single block from being driven into the woodwork of the car-body by any excessive external shock to the outer guard rail.

A plate 34 is provided at the bottom front 40 end of the door, to act as a keeper for the door when closed and its free end is designed to operate in the guide track *g*.

To operate the door, a hasp 21 is used to impart a cranking motion to the rod 10, which causes the rear end of the door to be 45 extracted from the opening. When the rod 10 has reached the limit of its movement the door can then be opened by sliding it along the track *t*, the guide-track *g* acting to guide the bottom of the door to its opening position.

In closing, the reverse of the operations recited above is performed, the inwardly disposed portions of the track *t*, and the guide track *g* serving to direct the front 55 end of the door into the opening.

The invention having been set forth, what is claimed as new and useful is:—

1. A track having a guide slot with adjacent rounded upper corner edges, hangers having globular heads arranged in the track and provided with spherical bearings,

each of said bearings being of one diameter, and spherical roller members, each of said roller members being of less diameter than each of the spherical bearings, the bearings being of such larger diameters than the roller members, as to permit the roller members to first roll in said bearing and roll on said corner edges and then subsequently to overcoming the inertia, slip in 65 said bearings, and roll continuously on the adjacent rounded upper corner edges. 70

2. If a hanger for car doors, a ball, a hanger having a semi-spherical cup having opposite side arms, a tubular track designed 75 to permit a continuously rolling movement of the ball on the track, said cup of the hanger being of such a larger radius than the ball and blending into said arms, whereby the hanger will begin its movement with 80 an alternate rolling and slipping of the ball, which in its movement gradually diminishes to a continuous slipping in said cup, the ball to begin a rolling motion in the hanger and a rolling motion on the 85 track, and then gradually substantially instantly subsequently diminishing to a continuous slipping in the cup and a continuous rolling on said track.

3. In a device as set forth, the combination of a tubular track rail having connections with the side of the car body, and provided with a longitudinal guide slot, a hanger having a globular head and being arranged in the track and provided with a 95 spherical bearing, a spherical device of less diameter than the spherical bearing, said spherical device being of such less diameter than the spherical bearing as to permit the device to first roll in said bearing 100 and roll in the tubular track rail, and then subsequently to overcoming the inertia, slip in the spherical bearing, and roll continuously in the track rail.

4. In a hanger for car doors and the 105 like, a hanger, a ball therein, said hanger having a cup of larger radius than the ball, a hollow track permitting a continuously rolling movement of the ball, said cup of the hanger blending into supporting means 110 for the door, whereby the hanger will begin its movement with an alternate rolling and slipping of the ball, which in its movement gradually diminishes to a continuous slipping in said cup.

In witness whereof, the applicant's signature is hereunto affixed in the presence of two witnesses.

EDWARD F. WOOD.
